UNITED STATES PATENT OFFICE.

LOUIS WILLIAM PIETSCH, OF POST FALLS, IDAHO.

SMOKE-ELIMINATING AND DRAFT APPARATUS FOR FURNACES.

1,124,513.

Specification of Letters Patent.

Patented Jan. 12, 1915.

Application filed March 25, 1913. Serial No. 756,641.

To all whom it may concern:

Be it known that I, LOUIS WILLIAM PIETSCH, a citizen of the United States, residing at Post Falls, in the county of 5 Kootenai and State of Idaho, have invented certain new and useful Improvements in Smoke-Eliminating and Draft Apparatus for Furnaces, of which the following is a specification.

10 This invention relates to improvements in smoke eliminating and draft apparatus for furnaces and one of the objects of the invention is to collect the soot from smoke during passage of the latter through the 15 apparatus in such a manner that the discharge from the chimney will merely consist of a colorless gas or vapor.

A further object of the invention is to provide a soot collecting apparatus, adapted to contain a suitable liquid, and provided with means for depositing metallic substances carried by the products of combustion so as to collect such metals and prevent waste thereof when the collecting 25 liquid is withdrawn for renewal purposes.

In the most improved embodiment of this invention I provide spaced receivers for the smoke, one adapted for reception of the smoke from the furnace and being connected with the other by a plurality of conducting pipes, the remaining receiver being provided with means for maintaining an induced draft through the apparatus.

Other features of the novelty will be 35 more fully described in connection with the accompanying drawings, and will be more particularly pointed out in and by the appended claims.

In the drawings: Figure 1 is a view in 40 side elevation of one form of my invention showing parts broken away. Fig. 2 is a sectional view on line 2—2 of Fig. 1. Fig. 3 is a sectional view on line 3—3 of Fig. 1. Fig. 4 is a perspective view of the construction shown in Fig. 3 in elevation. Fig. 5 is a plan view of the construction shown in Fig. 4. Fig. 6 is a detached perspective view of a reduced pipe section illustrated in Fig. 3. Fig. 7 is a perspective view of a 45 closure plate. Fig. 8 is a perspective view of a screen.

Like characters of reference designate similar parts throughout the different figures of the drawings.

50 As illustrated, the device of my invention includes spaced casings or smoke receivers

1 and 2, the former being adapted for direct connection with the furnace to receive the products of combustion therefrom. The receiver 1 is preferably provided with 60 baffle plates 3 which are arranged and disposed to cause the smoke to take a tortuous or circuitous path through the receiver 1. A further function is to arrest and prevent coarser particles, carried by the products 65 of combustion, from passing through casing 1. Casings 1 and 2 are connected with each other by a plurality of smoke conducting pipes in which are interposed pipe sections containing soot or smoke eliminating 70 means together with electrical means for depositing certain metallic substances, the foregoing being one of the most important features of the invention.

In the specific construction shown I provide three rows of piping, each row consisting of three pipes and designated by 4, 5 and 6. The pipes 4, 5 and 6 communicate with casing 1 in the rear thereof, with respect to the path of the smoke as is indicated by the arrow, and said piping 4, 5 and 6 preferably extend horizontally from said casing with elbows 7, 8 and 9 terminating vertically. Dampers 10, 11 and 12, one for each pipe, provide means for regulating or 85 cutting any of said pipes out of service. Upon the vertically terminating elbows are disposed pipe sections 13, 14 and 15 which are preferably formed of vitrified material or any material which is a non-conductor of 90 electricity, the purpose and construction of which will be hereinafter more fully described. The sections 13, 14 and 15 deliver to piping 16, 17 and 18 of relatively reduced size with respect to the sections 13, 14 and 95 15, and the piping 16, 17 and 18 delivers to casing 2, as clearly shown in Figs. 1 and 2.

Means is provided for maintaining an induced draft through the apparatus and such means may consist of a fan 19 directly connected with a motor 20, both of which may be disposed in the casing 2, and the casing 2 is provided with an outlet 21. Each section 13, 14 and 15 is composed of two parts of identical construction disposed in superposed relation and therefore only one part section will be described in detail, reference being made more particularly to Figs. 3, 4 and 5. One of the superposed sections is shown in Fig. 3 provided with a flange 22 110 adapted to seat upon an inclosing or housing flange 23 of the terminal 7. The upper

end of section 3 is provided with a closure disk seat 24, for a closure disk 25, and also with a recessed seat 26 adapted to receive the lower flanged end of the superposed section. Suitable locking means is provided for securing the superposed sections in place, and such means may consist of pivoted retaining elements 27 having handle portions 28 and lug portions 29. When the elements 27 are shifted on their pivots the lug portions 29 may be brought in overlapping and locking relation with the flange of the superposed section which may be disposed in the recessed seat 26.

15 The closure disk 25 may be provided with notches 30 adapted to be brought in registry with lugs 31, for assembling purposes, and the disk 25 may thereafter be shifted or turned to dispose the notches 30 out of registry with the lugs 31 so as to lock the disk 23 against upward movement. The closure disk 25 acts as a support for an outlet pipe section 32 which is provided with a flange 33 adapted to be disposed in a recessed seat 34 in the disk 25. The flange 33 is provided with notches 36 adapted to be brought into registry with lugs 37, when the parts are assembled, and thereafter shifted or turned out of registry therewith to lock the outlet pipe section in place against upward displacement. Near the lower end of the outlet section 32 I provide a shoulder 38 adapted to support a reticulated sieve or screen 39 which may as shown be of cylindrical formation with open ends. The screen 39 may be secured to a ring 40 adapted to seat on the shoulder 38. The screen 39 is preferably formed of metal. A metallic frame which may consist of rods or bars 41, is mounted 45 upon the outlet pipe section 32 and said bars or rods may be connected with the flange 33 thereof, as shown in Fig. 3. The bars 41 are electrically connected with each other by a band 42.

45 I have diagrammatically illustrated an electric circuit including a source of current 43 with one pole thereof connected by line 44 with screen 39, and the other pole thereof connected by line 45 with band 42. A switch 46 may be interposed in the circuit to cut the same into and out of operation. The frame bars 41 may form the cathode and the screen 39 the anode for effecting electro-deposition of certain metals carried 55 by the products of combustion. Within the section 13 is a collecting cup 47 which may be formed integral with the section 13 and which may be suspended therein by webs or flanges 48 which are spaced apart so as to 60 leave a passage for smoke between the cup 47 and the interior wall of section 13. The path of the smoke through section 13 is indicated by the arrows and it will be seen that the imperforate end 49 of the cup faces 65 the incoming smoke while the open end 50 is

disposed above the lower end of the outlet section 32. The cup 47 is adapted to contain a smoke eliminating and collecting liquid, which may be water, and the level of the liquid is maintained as shown above the 70 lower end of section 32 so as to form a trap through which the smoke must pass from section 13 to section 32. Near the lower end of section 32 I provide a plurality of openings 32' through which the vapor may pass 75 when the induced draft is low and perhaps not sufficient to conduct the vapor below the lower margin of section 32. It will also be seen that the screen 39 and the lower ends of bars 41 are immersed in the liquid thereby 80 permitting said parts to be used for electrodeposition of any valuable metal thereon. The passage of the smoke through the liquid serves to collect the soot and all other matter or substances carried by the smoke so 85 that the discharge at 21 will be a colorless vapor.

The collecting cup 49 is provided with an outlet pipe 51 which leads from the bottom of the cup so as to effectively drain all of 90 the contents therefrom. The pipe 51 extends through section 13 and may be provided with any suitable form of valve closure such as a pet cock 52. An intake pipe 53 leads through section 13 to cup 49 and is 95 provided with a flared funneled terminal 54 to facilitate the pouring of liquid therein. The intake pipe 53 may also be provided with a valve closure 55. It will thus be seen that when the collecting liquids are 100 fully impregnated the cups of any pipe may be readily emptied and cleaned and the pipe of such cup may be thrown out of service by turning the damper thereof, and this may be accomplished without impairing the 105 efficiency of the apparatus as regards the other piping. After all matter has been eliminated from the smoke to reduce the same to a colorless vapor, by passage of the smoke through the collecting liquid, the volume will be greatly reduced and therefore 110 the outlet pipes 32 are reduced in size with respect to sections 13 and the extension piping 16, 17 and 18 are still further reduced so as to permit the use of a fan of relatively 115 small size and at the same time obtain an efficient induced draft, it being understood that the reduction in cross section of the piping, corresponding to the reduction in volume of the contents passing therethrough 120 greatly reduces the area through which the draft is to be maintained.

In the operation of furnaces for various commercial purposes a great deal of expense has been heretofore necessitated in building 125 high chimneys so as to discharge the fumes and gases at a high elevation from the earth owing to the injurious effects upon vegetation and even when such gases and fumes are discharged at a high elevation such injuri- 130

ous effects are not avoided. It will be seen that by the provision of my improved draft apparatus the height of the chimney or stack for affording the necessary draft is not only 5 entirely avoided, but in addition, I am able to entirely eliminate the discharge of noxious chemical substances and can also preserve residual portions thereof which may be valuable. Such materials as may be acted 10 upon by electrolysis may be deposited on the bars 41 or the screen 39 and such matter as may be without value, but which would be detrimental if discharged, may be collected and taken care of through the 15 cups 49.

While I have herein shown and described one specific embodiment of my invention, I do not wish to be limited thereto except 20 for such limitations as the claims may import.

I claim:—

1. In a spark arrester, a conducting pipe having an upright cylindrical pipe section of vitrified material interposed therein and 25 including a cylindrical cup mounted in said upright section between the ends thereof in concentric spaced relation with respect to the interior of said section, said cup and section having superposed inlet and outlet 30 pipes formed integral therewith and extending through said section and opening into said cup, the upper end of said section having an inner annular closure seat portion and an outer annular pipe seat portion one 35 being above the other, a disk pipe supporting closure disposed in said closure seat por-

tion and provided with an opening having a pipe seat therein, an outlet pipe projecting downwardly through said closure opening into said cup and having its upper end 40 provided with a flange engaging the seat in said closure opening, and a pipe section having its lower end disposed in the outer pipe seat portion of said upright section, substantially as described. 45

2. In a spark arrester, a conducting pipe having an upright cylindrical pipe section interposed therein and including a cylindrical cup mounted in said section between the ends thereof in spaced relation with respect 50 to the interior of said section, the upper end of said section having an inner annular closure seat portion and an outer annular pipe seat portion, the latter being above the former, a disk pipe supporting closure 55 disposed in said closure seat to close egress through the upper end of said section and provided with an opening having an outlet pipe seat therein, an outlet pipe projecting downwardly through said closure seat open- 60 ing into said cup and having its upper end provided with a flange engaging the seat in said closure, and a pipe section having its lower end disposed in the outer pipe seat of said upright section, substantially as de- 65 scribed.

In testimony whereof I affix my signature in presence of two witnesses.

LOUIS WILLIAM PIETSCH.
